Primary Examiner — T Chase Nelson*Assistant Examiner* — Jonathan J. Han(74) *Attorney, Agent, or Firm* — Warner Norcross + Judd LLP(57) **CLAIM**

The ornamental design for a footwear sole, as shown and described.

DESCRIPTION

FIG. 1 is a perspective view of the footwear sole embodying the new design;

FIG. 2 is a bottom view thereof;

FIG. 3 is a right side view thereof;

FIG. 4 is a left side view thereof;

FIG. 5 is a front view thereof; and,

FIG. 6 is a rear view thereof.

The broken lines depicting an article of footwear in FIGS. 1–6 are shown for environmental purposes and form no part of the claimed design. Further, the broken lines immediately adjacent to the solid-line portions depict boundary of the design, with the broken lines forming no part of the claimed design.

1 Claim, 5 Drawing Sheets(56)
